2,395,619

SPECIAL LOUVER-TYPE VENTILATOR FOR
SHIP PortholesAndrew Paul Fischer and Hazel Fischer,
San Francisco, Calif.

Application February 11, 1944, Serial No. 521,986

2 Claims. (Cl. 98—121)

This invention relates to an especially designed louver type ventilator for disposition in a porthole of a ship, and the outstanding purpose of said ventilator is to function as a "blackout" closure while at the same time promoting requisite air circulation for cabin ventilating use.

In reducing the preferred embodiment of the invention to actual practice I have conceived of a structural arrangement of carefully chosen and inter-related coacting elements thus providing a device susceptible of quantity production on a mass basis, whereby to provide an ideal type ventilator fulfilling the requirements of both the manufacturer, the trade, and users.

More specifically, I have evolved for practical and expedient use a ventilator characterized by a special adaptation and arrangement of louvers to thus provide a light-proof unit readily insertable and removable and susceptible of bodily adjustment in an orbital path to position the louvers in varying angular position to serve either as so-called air scoops, or as rearwardly facing suction vanes.

Other features and advantages of the invention will become more readily apparent from the following description and the accompanying illustrative drawings.

In the drawings, wherein like numerals are employed to designate like parts throughout the views:

Figure 1 is a fragmentary inside elevational view of a special louver-type "blackout" ventilator constructed in accordance with the preferred principles of the instant invention.

Figure 2 is a fragmentary elevational view of one-half of the structure observing the side opposite to that seen in Figure 1, this to bring out the position of the crank controlled positioning and retaining lug.

Figure 3 is an enlarged detailing and fragmentary sectional view, this on the line 3—3 of Figure 1 looking in the direction of the arrows.

Figure 4 is a fragmentary peripheral or edge elevational view showing both sides of the device and the crank and lug retaining means.

Figure 5 is a fragmentary sectional view showing a modified form of the invention.

The ventilator, as a unit, is denoted by the numeral 6. It is shaped and proportioned to slip into the portholes 7 of the hull of the ship as brought out to advantage in Figure 3. It is constructed of sheet metal or equivalent sheet material to render it sufficiently strong and durable. The main frame 8 is of annular form and (see Figure 3) is provided inwardly of one edge with

a marginal or circumferential V-shaped channel defining an assembling shoulder or bead 9 for the outside disk-plate 10. This plate fits tightly within the frame 8 and abuts the bead 9 and may be soldered or otherwise secured if necessary. The plate is provided with horizontal parallel slots 11 constituting the exterior ventilating openings. Coacting with each slot is a hood-like louver 12. The lower free edge portion of the louvers 12 is disposed on a plane approximately even with the bottom of the coacting slot 11. Also the interior louvers 14 are positioned opposite the slots 11, each louver element having an attaching flange 15. This particular louver is deeper than the complementary outside louver and, therefore, has its lower edge portion extending considerably below the edge of the slot. This provides for free circulation of air and at the same time forms a substantially light-proof ventilation arrangement. It will be noticed also in Figure 3 that the intermediate portion of the annular shell or frame is provided with struck-out drainage or seepage cups 8a. The inboard marginal edge of the frame is provided with a radially outstanding flange 16, this to coact with the embracing hooked marginal flange 17 carried by the inside disk plate 18. This plate 18 like the plate 10 is provided with horizontally elongated slots 19 for ventilating and over each slot and on the right thereof is a scoop or hood-like louver 20. Further, in this arrangement I provide internal louvers 21 having attaching flanges soldered or otherwise secured in place on the inner surface of said plate. These louvers 21 correspond to the coacting or opposed louvers 14. They are of a depth or cross-sectional dimension to well cover the coacting ventilating slots 19. The interlocking marginal arrangement provided by the two flanges 16 and 17 provides satisfactory ways and means of holding the entire structure nicely in place, that is, in place against the surrounding gasket or packing ring 23. At diametrically opposite points I provide rotatably mounted shafts 24 each having a hand crank 25 at its inner end and a wedging-type lug or retaining detent 26 at the inner end. These lugs engage the marginal portion of the porthole frame to thus securely mount the device in operative position.

In some instances it is possible to use a wooden frame-work such as is shown for example, in Figure 5 at 27. In this instance, the two louver-equipped plates or disks 28 and 29 are arranged in parallelism and secured by nails or equivalent fasteners 30 to the surrounding frame-work. The louvers and slots are the same as already de-

scribed and are, therefore, denoted by the same reference numerals.

It is within the sphere or scope of the invention to vary the configuration from circular to rectangular or some other form and to use the structure in building wall openings such as for example, photographic laboratories or any place requiring ventilation without admitting daylight. It is also to be pointed out that the incorporation of a screen is optional, though the same is desirable in tropical zones and locations and may be mounted in the frame between the louvers 14 and 21. The compact construction and arrangement is such as to permit a porthole to be closed by the usual glass cover (not shown) without necessitating removal of the device from the porthole.

The structure may be rotated in any direction, with the opening of the fins or louvers turned in the direction in which the ship is proceeding, they to act as air scoops. Or the structure may be turned in an opposite position at which time the louvers act as air exhausts. By facing the louver arrangement up or down the effect on air circulation is virtually nil.

The entire arrangement, with the exception of the fasten-lugs and insect screen is constructed of light metal, but due to its construction is quite rigid. The insides of the louvers or vanes are painted dark, that is, jet black to prevent any reflection of light rays. It is evident, therefore, that the structure aptly fulfills the requirement of a device in this category and fulfills a long felt need for proper ship accessories in "blackout" areas, particularly in tropical zones.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A "blackout" type ship porthole ventilator comprising a substantially annular frame, the in-board end of said frame having an outstanding endless circumferential flange, a disk-like interior closing plate having a marginal flange interlocking with the first-named flange, said disk-like plate having a plurality of horizontal slots, integral louvers on the outer side of said plate registering with the slots, said louvers having the lower edges thereof terminating substantially even in a plane with the lower edges of the slots, internal louvers considerably greater in depth than the first-named louvers and having flanges attached to the interior surface of the plate, the last mentioned louvers depending below the lower edges of said slots, a corresponding type slot and louver-equipped plate closing the outboard end portion of said frame, and the intermediate portion of the frame being provided with circumferentially spaced drainage holes.
2. A ventilator for portholes and the like comprising a tubular frame open at inner and outer ends and being of a diameter adapting it to be thrust into a porthole through the inner end thereof and provided at its inner end with outstanding abutment means for engaging margins of the porthole and limiting outward movement of the frame through the porthole, inner and outer end plates carried by said frame, each end plate being formed with a plurality of transverse slots constituting air passages spaced from each other, one above another, louvers carried by said plates and projecting outwardly therefrom along upper edges and ends of said slots and having their lower edges substantially flush with the planes of lower edges of the slots, and other louvers carried by said plates and projecting from inner faces of the plates along upper edges and ends of the slots and being of appreciably greater depth than the slots and the first-mentioned louvers and projecting downward below lower edges of the slots an appreciable distance.

ANDREW PAUL FISCHER.
HAZEL FISCHER.
